ELECTRIC CABLE POTHEAD

Filed Feb. 24, 1930

UNITED STATES PATENT OFFICE

GEORGE A. MATTHEWS, OF DETROIT, MICHIGAN

ELECTRIC CABLE POTHHEAD

Application filed February 24, 1930. Serial No. 430,780.

- This invention relates to means for protecting high potential systems when changing from one medium to another, and particularly to the special type of devices known as pot-heads.
- It is the object of this invention to provide an improved medium in which conductors carrying a high voltage may be safely spaced when discontinuing insulation such as is used for underground cables in changing to the spacing required for aerial conductors.
- It is a more specific object of the invention to provide a pothead in which oil may be used as an insulating medium, and to provide a structure which will be of minimum size and reduced weight so that the quantity of oil required will, consequently, be a minimum.
- It is a further object to provide a pothead which is adaptable for connection with a remotely located oil reservoir and which will retain a sufficient amount of oil therein for safe operation in case of leakage or a break in the oil line from the reservoir.
- It is a further object of the invention to provide an efficient moisture seal for the ends of the cables, this moisture seal also acting to retain oil in the pothead.
- It is a still further object to provide a pothead through which the cable conductors may be carried with a minimum of bending so that the insulation thereon may not be damaged as by cracking or creasing.
- It is a further object to provide suitable supports for the conductors which may be entirely capable of withstanding the longitudinal and tangential stresses to which they may be subjected. It is well known that a wire carrying a high voltage, when short-circuited, exerts an enormous force tending to straighten itself so that the supports just referred to will be understood to cooperate with the object above named, having the conductor assume a substantially straight course through the pothead. It is to be noted that this characteristic of a high potential wire has, heretofore, presented one of the greatest problems in the construction of potheads, and has been a continuous source of trouble in conventional potheads.
- It is a further object to provide a porcelain
- bushing for all connector parts and to so provide for the replacement of any broken bushing without disturbing any of the others.
- A still further object is to provide a base opening in the pothead body to facilitate the training of conductors and to allow inspection of the cable crotch at the point of entrance.
- Another object is to provide a clamping flange over the end of the cable sheathing to effect an oil tight union with the lead sheath within the cable conduit, the clamping flange to be provided with a lead ring soldered into a tinned groove to which the cable sheath may be soldered.
- Other objects are to provide a pothead having neat body lines in order to harmonize with any well designed installation, to provide a structure which will readily lend itself to installation by a mechanic using ordinary care and ordinary tools and not requiring wiped joints and like operations.
- It is still another object to design a pothead in such a way that bushing type current transformers can be installed over the tubes enclosing the individual conductors.
- Other objects and advantages will become apparent as reference is had to the accompanying drawing wherein is illustrated, by way of example only, one embodiment of my invention and in which:
- The figure is a side elevation, partly broken away for purposes of explanation, of my improved pothead.
- Referring more particularly to the drawing, numeral 1 designates my improved pothead as a whole which is composed of a pothead body 2 having conductor housings 3 radiating therefrom in the form of tubing to each of which is attached at the end thereof a porcelain bushing 4 by means of a collar 5 which is secured to tubing 3 by bolts 6 and secured against leakage by washers 7. The bushing 4 carries at its outer end an open ended cap 8 having upwardly converging sides through which a plug 9 extends, the purpose of which will hereinafter become apparent. Over the end of cap 8 is placed a washer 10 against which rests a bell cap 11

having an opening 12 in the outer end thereof for reception of a conductor through which current may be taken from the pothead. The bell portion of cap 11 houses the 5 plug 9 and acts to restrain moisture from contacting the washer 10 and thence finding its way into tubing 3.

Interiorly of cap 11 is fitted, preferably by screwing, a bolt 13 having a cap 14 as its 10 head. The cap 14 acts as a connector receiving in a soldered joint the end of a conductor 15.

A cable 16 containing a plurality of conductors, illustrated as being three in number 15 and designated, 17, 18 and 19, is of conventional type with conventional insulation and conventional lead sheathing such as is used in leading conductors underground. Upon changing from the insulation commonly 20 used for underground conductors to aerial conductors, it is necessary to space the individual conductors comprising the cable so that an air gap of sufficient size to replace the insulation may be had. In spreading 25 the individual conductors, each branch is led through an individual tube 3, then bushing 4 and is reduced in size to form what has been described as a smaller conductor 15 for co-operation with connector 14.

30 In order that proper insulation may be provided for the individual conductors at the point of spread and vicinity, the pothead body 2 is hollowed out somewhat as shown in the drawing whereby it may contain a 35 suitable amount of insulation which I provide in the form of oil. For the purpose of supplying oil to the body 2 there is a pipe line 30 leading from any suitable source of supply, not shown, to any desired point 40 in the pothead. When providing a line from a remote point, leakage or breakage is liable to occur so that I connect pipe 17 into the top of one of tubes 3. Thus, if breakage 45 or leakage occurs, the oil level in the pothead may not fall below the level of the point of entrance and the body 2 is guaranteed of containing a sufficient supply to 50 guarantee safe operation.

55 In leading the conductors through the pothead body, it is desirable to lead them with a minimum of bending for two reasons, first, the insulation on the conductors is less likely to crack or crease and, secondly, an enormous force is exerted by the conductor to straighten itself in case of a short-circuit anywhere along the line. In order to provide direct supporting means for preventing straightening of the conductor, I provide an 60 insulated sheath 31 within each tube 3 in spaced relation with the sides. A conical metallic collar 32 is securely mounted on each conductor at the end of the sheath so that the force exerted at the point of bend 65 will be directly assumed by the sheath and

the connection at the connector 14 free from danger of being pulled loose.

The tubes containing the conductors diverge from the body 2 and are braced in spaced relation by supports 33.

70 The base of body 2 is formed in such a way as to be suited for mounting directly on the cable. Thus a collar 20 may fit around the cable prior to entering the pothead. The lead sheath of the cable 16 is flared outwardly to 75 conform to the shape of a flared portion 21. Embedded in the portion 21 is a lead ring 22 which may be soldered to portion 21 and also to the flared lead sheathing. On top of the portion 21 is a washer 23. The pothead base is of conformation to fit the collar 20 while resting on the washer 23 so that as the collar and pothead are drawn together by means of bolts 24 the washer 23 and lead ring 22 form 80 a very efficient seal to retain the oil and to 85 keep out moisture.

A plate 25 is provided, as shown, in order to allow of training the conductors through their respective tubes, to permit of inspection at the pothead crotch and to permit of 90 cleaning when desired.

95 After plates 25 have been secured bolted in place, plugs 9 are removed from each tube and oil may then be fed into the pothead through pipe 30 from the source of supply. As soon as oil overflows and runs out of the plug openings, the plugs are then replaced.

I am aware that numerous details of construction may be varied through a wide range without departing from the principles of this 100 invention, and I therefore do not purpose limiting the patent granted, otherwise than necessitated by the prior art.

I claim as my invention:

1. In a pothead, the combination of a pot-head body arranged for securing to a supporting structure, an elongated metallic tubular member for forming a cable housing and having one end rigidly secured to said body, a bushing secured at the other end of said 105 member spaced from said body and having a terminal connection at its outer end, an insulated cable extending into said body, through said member and bushing where it is connected to said terminal, a sheath of insulating material surrounding said cable, and means adjacent the ends of said member for supporting and centering said sheath within 110 said housing.

115 2. In a pothead, the combination of a pot-head body arranged for securing to a supporting structure, a plurality of elongated metallic tubular members secured to said body so as to diverge outwardly therefrom and form individual cable housings, bushings secured respectively at the outer ends of said members having terminal connectors, means for bringing a multi-conductor cable into said body adjacent the inner ends of said members, the conductors of said cable being indi- 120 125 130 135

vidually carried through said body, members and bushings, and secured to said terminals, sheaths of insulating material surrounding the cables within the housings, means adjacent the ends of said tubular members for supporting and centering said sheaths within the housings, said sheaths being extended past their inner supports into said body for supporting the conductors between the cable and tubular members.

In testimony whereof I have hereunto subscribed my name at Detroit, Wayne County, Michigan.

GEORGE A. MATTHEWS.
